Primary Examiner — Lauren D Mcvey*Assistant Examiner* — Mai Shim(74) Attorney, Agent, or Firm — JEEN IP LAW, LLC(57) CLAIM

The ornamental design for a brush, as shown and described.

DESCRIPTION

FIG. 1 is a perspective view of a brush, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion 9 taken from FIG. 1. The dash-dash broken lines depict the boundaries of the enlargement that form no part of the claimed design.
